DESIGN FOR A GAME PIECE

George Saxmann, Hendersonville, N. C.

Application September 28, 1934, Serial No. 53,424

Term of patent 14 years

To all whom it may concern:

Be it known that I, George Saxmann, a citizen of the United States, residing at Hendersonville, in the county of Henderson and State of North Carolina, have invented a new, original, and ornamental Design for a Game Piece, of which the following is a specification, reference being had to the accompanying drawing, forming a part hereof.

The figure is a perspective view of a game piece showing my new design.

The invention resides in a game piece of the configuration shown having the ornamental band disposed intermediate the end portions; the said end portions being of contrasting colors and provided with grooves in their opposed faces.

I claim:

The ornamental design for a game piece, as shown and described.

GEORGE SAXMANN
